United States Patent

Des. 242,292
Patented Nov. 9, 1976

242,292

FOOT BATH

Scott W. Miller, Stratford, James Bartlett Wyatt, Stamford, and Kenneth Van Dyck, Westport, Conn., assignors to Clairol Incorporated, New York, N.Y.

Filed Dec. 13, 1974, Ser. No. 532,424

Term of patent 14 years

Int. Cl. D24—04

U.S. CL. D83—1 C

Published under the Second Trial Voluntary Protest
Program on Feb. 10, 1976, as document No. B532,424

FIG. 1 is a perspective view of a foot bath showing our new design;

FIG. 2 is a side elevational view, the opposite side being a mirror image of the side shown;

FIG. 3 is a front elevational view;

FIG. 4 is a top plan view;

FIG. 5 is a bottom plan view; and

FIG. 6 is a rear elevational view thereof.

We claim:

The ornamental design for a foot bath, as shown and described.
